UNITED STATES PATENT OFFICE.

CHESTER F. GAILOR, OF BROOKLYN, NEW YORK, AND CHARLES H. CLARK, OF CLEVELAND, OHIO.

RAILWAY-TRACK CONSTRUCTION.

Application filed November 19, 1921. Serial No. 516,287.

To all whom it may concern:

Be it known that we, CHESTER F. GAILOR and CHARLES H. CLARK, both citizens of the United States, and residents, respectively, 5 of the borough of Brooklyn, county of Kings, city and State of New York, and of Cleveland, in the county of Cuyahoga and State of Ohio, have jointly invented certain new and useful Improvements in Railway-10 Track Construction, of which the following is a specification.

Our invention relates to rail tracks, particularly for street railways, and has for its object to provide a strong and readily laid 15 track construction, easily adapted to various conditions, permanently holding the parts in proper relation, and, in its preferred embodiment, assuring a practically noiseless character of the track.

Several satisfactory embodiments of our 20 invention will now be described in detail with reference to the accompanying drawings, and the features of novelty will then be pointed out in the appended claims.

In the said drawings, Fig. 1 is a plan view 25 of a track constructed according to our invention;

Fig. 2 is a cross section thereof on line 2—2 of Fig. 1;

Fig. 3 is an enlarged cross section of one 30 of the rails and its support on line 3—3 of Fig. 1;

Fig. 4 is a cross section illustrating a step 35 in the manufacture of our improved rail supports or ties;

Fig. 5 is a view similar to Fig. 3 but showing 40 the tie laid inclined instead of horizontal;

Fig. 6 is a view similar to Fig. 2 but showing 45 a slightly different construction;

Fig. 7 is a cross section of still another 50 form of our invention, on the plane indicated by the line 7—7 of Fig. 8, and

Fig. 8 is a longitudinal section on the line 55 8—8 of Fig. 7.

In the forms of our improved construction 60 illustrated by Figs. 1 to 6 inclusive, the rail supports are not continuous from one rail to the other, as the usual cross ties, but are 65 provided for each rail individually, as shown best in Fig. 1. This view also shows the preferred arrangement of the rail supports 70 in pairs, with the two members of each

pair in transverse alignment. The supports 75 are disposed at suitable distances from each other along the track.

Each of the supports shown in Figs. 1 to 80 6 is made from flat sheet steel formed into a top member 10 adjacent to the base A of the rail, and with downwardly diverging 60 longitudinal side members 11, these members forming together a trapezoidal channel or chamber open at the bottom. At suitable points tongues or like portions of metal are 85 punched out of the members 10 and 11 and bent inwardly to project into said chamber, as indicated at 12 and 13 respectively. Other portions, in the form of lugs or clips 14, are punched out and bent outwardly or upwardly from the top member 10, these clips 70 (of which there are generally at least four to each support) extending lengthwise of the track, and being arranged to project over the two edges of the rail base A as shown.

The chamber formed by the members 10 75 and 11 is adapted to be filled with concrete, the tongues or other inward projections 12, 13 forming steel reinforcing members embedded in such concrete. We prefer to fill 80 the concrete 15 into said chamber while the support is inverted as shown in Fig. 4, being held in such position by a suitable frame 16. This frame has end walls to close the 85 open ends of the chamber of the support and thus better hold the concrete. This special 90 manner of applying the concrete, with the rail support inverted so that its inclined side walls will converge downwardly, will insure a homogeneous character of the concrete and a much better connection of the 95 concrete with the metal than is the case with present steel ties, for the reason that since the body of concrete and the chamber containing it taper downwardly, the concrete is very liable to with concreted steel ties as made hitherto. The filling of the supports 100 with concrete in the manner described may be done in the yards or at any other suitable place before the supports are brought to the track. The openings formed in the top member 10 and side members 11 by punching out 105 the tongues 12, 13 and clips 14, allow the air to escape readily from the inverted channel 10, 11 when the concrete is filled in.

The rail-holding clips 14 take the place of

spikes or similar rail-fastenings employed usually. To fasten the rails after they have been placed on the improved supports, the clips 14 are hammered or otherwise driven 5 down until they are in firm contact with the rail base A. As this may prove difficult in practice, we generally drive small wedges or other suitable fasteners 17 between the upper surface of the rail base and the lower surfaces 10 of the clips 14, and preferably these fasteners 17 are then welded to the rails. In most cases we prefer not to have the rail base A rest directly on the top member 10, but on an interposed flat cushion 18 which 15 may consist of asbestos-asphalt or other suitable material, this cushion or filler preferably being of the same width as the rail base, and as long as the top member 10. We thus obtain a cushion effect which will 20 deaden and eliminate most of the noise now common to most street railway track structures in paved streets.

To establish and preserve the proper gauge, we prefer to connect the supports 25 engaging the two rails of the same track, by tie members or rods 19 located at the upper portions of the supports, preferably slightly below the level of the top member 10. These tie rods are preferably welded to the side members 11 at the four points designated by 20, but the connection of the tie rods with the rail supports might be effected in other ways, as by fastening said rods to lugs or ears punched from the front 25 edges and rear edges of said supports. These rods may be made of cheap material, since they act chiefly as tension members.

Preferably the tie rods 19 should not be 40 exposed, but embedded in the upper portion of the so-called base concrete 21 in which the concreted rail-supports are placed, such base concrete being in contact with the concrete 15 filling the rail support, the concrete bodies 15 and 21 when set forming practically a continuous unitary solid mass. The embedding of the rods 19 in the base concrete 21 also acts as a reinforcement for such concrete. The upper surface of the base concrete 21 is generally either flush with or above the upper surfaces of the top members 10. In some cases, or at some portions of the track, where for special reasons the tie rods 19 are not thought sufficient, we may employ additional tie rods 22 connecting the lower portions of the side members 11, as indicated in Figs. 2 and 6. These lower tie rods 22 might be placed directly below some or all of the upper tie rods 19, and connected with the side members 11 in the same manner as described with reference to said upper rods. The lower rods 22 might, however, connect the supports of the two rails at portions of said 65 supports other than their front or rear

edges, and would be located at intervals suited to the particular conditions which render it advisable to employ such additional tie rods.

The improved rail supports could have 70 their top members 10 horizontal as shown in Figs. 2, 3 and 6, but in order to secure a uniform contact between the rail head and the tread of a standard wheel, the supports could be inclined transversely as indicated 75 in Fig. 5 to take into account the slightly conical shape of the tread of the wheel C. It will be observed that this transverse inclination of the rail support (and the elevation of the outer rail on a curve, if desired) can be obtained much more conveniently with our invention having separate supports for the two rails, than with ordinary steel ties which are connected directly with both rails. 80

Fig. 6 shows a complete street railway track with the pavement on top of the foundation or base concrete 21. This pavement is illustrated as comprising blocks 23 with joints grouted as indicated at 24, the heads and webs of the rails being likewise embedded in the grout. The other features of the track are as in Fig. 2. We thus obtain a monolithic structure in which the steel rails act as reinforcing members, yet notwithstanding the rigidity of the mass, the structure is practically noiseless as regards traffic on the rails, owing to the use of the fillers or cushions 18. In ordinary structures of this character, which are made 100 without such cushions, much trouble is experienced on account of the great noise as all jars, sounds and blows coming upon the rails are transmitted directly to the rigid mass of concrete. The cushions 18 also 105 press upwardly on the rail bases and make it easier to keep them in good contact with the clips 14.

When using separate supports for the two rails, as described with reference to Figs. 1, 2, and 6, the central portion between the rails, at their points of connection, will be practically unobstructed, thus making it much easier to work around, install and adjust the supports and their tie rods, and 110 tamp the concrete if necessary, than is the case with other types of ties or rail supports. 115

In the form of our invention illustrated by Figs. 7 and 8, the rail support comprising a top member 10' and downwardly diverging transverse side members 25, is made wide enough to support both rails of the track. Tie rods such as 19 and 22 are therefore not required in this construction, 120 although in case of relatively high rails, we may employ the well-known expedient of tie-rods connecting the rails directly. Projections 12' and 13' (similar to 12 and 13) may be provided on the members 10' 125 130

and 25 respectively, although it is not necessary that all of said members should be provided with such projections. We prefer to have the rail-supporting portions of the top member inclined downwardly toward each other, as shown in Fig. 7, thereby obtaining the same relative arrangement of rail head and car wheel as indicated in Fig. 5. It will be understood that in Fig. 5 as well as in Fig. 7 the incline of the rail-support will be downward toward the inside of the track, that is to say, the bases of the two rails will be inclined oppositely so as to converge downwardly.

In the several constructions shown, the punching out of projections from the members (10, 11, 10', 25) of the rail-support not only provides reinforcement for the body of concrete 15 contained within the support, but also forms in said members openings through which the base concrete 21 may enter to come into better contact with said concrete 15 and securely embed the rail supports in the base concrete. The rail supports shown in Figs. 7 and 8 preferably receive their concrete filling 15 while they are in an inverted position, in the same manner and with the same advantages as explained with reference to Fig. 4.

Our improved track construction provides almost double the support for the rails that is now furnished by other types of ties, and in the forms illustrated by Figs. 1 to 6, the central portion of the tie, which is of no great value in present monolithic street railway track construction, is eliminated. Even the form shown in Figs. 7 and 8 has the advantage of great simplicity and low cost of manufacture and installation. The work of placing our improved rail supports in position can be done with the simplest track tools. These supports are very light and therefore easily handled, the expense of handling and shipping them being correspondingly low. As the support, whether made actually in one section, as in Figs. 7 and 8, or of two sections connected by tie rods welded to them, is made in one piece with the rail fastenings or clips, this makes it impossible for the parts to work loose or to become unserviceable on account of rusting of threads, as in constructions including screws, nuts or like fastenings. The entire track structure reinforced as it is by our improved supports, is very durable yet owing to the cushions employed it avoids the objectionable rigidity of the present monolithic steel concrete track structures, and minimizes the noise produced by the cars.

The improved supports extend under a longer area of the rail bases than the usual cross ties and thus increase the solidity of the track. Owing to the more efficient support given to the rails, it will be possible to employ a much lighter rail section without im-

pairing the stability or the lasting qualities of the track and road bed. The improved construction will also insure greater freedom for the laying and repairing of the pavements than is now possible with constructions in which tie rods are fastened to the rails.

Removal and renewal of rails is also greatly facilitated by our invention, it being only necessary to heat the clips 14 and bend them upward in order to release the rails. The fillers or cushions 18 are then readily accessible for renewal, without in the least disturbing the rail supports and the concrete in which they are embedded.

Various modifications may be made without departing from the nature of our invention as set forth in the appended claims.

We claim:—

1. A track structure comprising rail supports each consisting of a top member and of downwardly-diverging side members, said supports having openings and tongues bent inwardly at said openings, and also having apertures and rail-holding clips bent outwardly from said apertures in said top members, rails held by said clips, and a body of concrete in which said supports are embedded.

2. A track structure comprising rail supports each consisting of a top member and of downwardly-diverging side members, said supports having openings and tongues bent inwardly at said openings, and also having apertures and rail-holding clips bent outwardly from said apertures in said top members, cushions set on said top members between said clips, rails the bases of which are fitted between said cushions and said clips, and a body of concrete in which said supports are embedded.

3. A track structure comprising rail supports each consisting of a top member and of downwardly-diverging side members which extend lengthwise of the track, rail-holding clips extending upwardly from said top member and toward each other, said oppositely extending clips being integral with such top member, a cushion set on said top member between such clips, and rails the bases of which are fitted between said cushions and said clips.

4. A track structure comprising rail supports each consisting of a top member and of downwardly-diverging side members which extend lengthwise of the track, rail-holding clips extending upwardly from said top member and toward each other, said oppositely extending clips being integral with such top member, a cushion set on said top member between such clips, rails the bases of which are fitted between said cushions and said clips, and fasteners fitted between said rail bases and said clips.

5. A track structure comprising rail sup-

- ports each consisting of a top member and of downwardly-diverging side members forming a channel with said top member, tongues extending from said support into said channel, rails resting on said supports, and a body of concrete in which said supports are embedded.
6. A track structure comprising channeled supports having tongues extending into their channels, rails resting on said supports, and a body of concrete in which said supports are embedded.
7. A track structure comprising channeled supports having openings and, adjacent thereto, tongues extending into the channels of the supports, rails resting on said supports, and a body of concrete in which said supports are embedded and which extends through said openings.
8. A rail support consisting of a body of sheet metal formed with a central member and side members diverging from said central member and forming a channel therewith, and projections extending from said support into said channel.
9. A rail-support consisting of a body of plate-like metal formed with a central member and side members extending from opposite edges of said central member and forming therewith a channel ranging lengthwise of the track, and oppositely-extending rail-holding clips located on the side of said cen-
- tral member opposite to such channel and integral with said central member.
10. A rail support consisting of a top member on which the rails are adapted to rest, and side members extending downwardly from such top member and provided with openings and with lugs extending adjacent to said openings into the channel formed by said top member and side members.
11. A track structure comprising two longitudinal series of rail-supports each consisting of a transversely-inclined top member and side members extending lengthwise of the track, and rails resting on the respective series of said supports, the top members of one series of supports being inclined transversely in the direction opposite to those of the other series.
12. The process of connecting rail-supports having downwardly-widening channels, with concrete, which consists in inverting such supports, so that the channels will have downwardly-converging surfaces, and then filling such channels with concrete so that the latter will, by gravity, be urged against said surfaces.

Signed at Cleveland, in the county of Cuyahoga, and State of Ohio, this 14th day of November, 1921.

CHESTER F. GAILOR.
CHARLES H. CLARK.
